REFRIGERATION SYSTEM

Marion R. Moore, Atlanta, Ga., assignor, by direct and mesne assignments, of one-third to C. L. Emerson, Atlanta, Ga., and one-third to Bryan M. Blackburn, Newnan, Ga.

Application April 25, 1932, Serial No. 607,474

9 Claims. (Cl. 62—125)

This invention relates to mechanical refrigeration, and it has for its general object the provision of a system particularly adapted to be installed in apartment buildings in which a plurality of evaporators located at different places or on different floors, are intercalated in a single system, inasmuch as the system of the present invention avoids the use of a compressor in the building and the consequent annoyance to the 5 occupants from noise and vibration incident to its operation, but it also provides a hermetic conduit of which the evaporating coils form a part in which the refrigerant is maintained below atmospheric pressure so that any possible leakage will be into and not out of the system, whereby in the event of leakage, the refrigerant will 10 not escape into the room atmosphere.

Still another object of the invention is the provision of a refrigeration system in which the 15 hermetic conduit including the evaporators, within the building, is in heat exchanging relationship, for condensation purposes, with a refrigeration system of any desired type located outside of the building, for example, on the roof.

A further object of the invention is the provision of the hermetically sealed conduit as above 20 described in automatic selective connection with condensers of dissimilar types, one including a heat exchanging element forming part of a refrigeration system and the other an atmospheric condenser.

Other objects of the invention will appear as 25 the following description of a preferred and practical embodiment thereof proceeds.

In the drawing which accompanies and forms a 30 part of the following specification, the sole figure is a diagrammatic representation of a refrigeration system such as the present invention contemplates, and which may be conveniently referred to as a duplex system since it in fact, involves in its more specific concept two refrigeration systems interlinked so that the condensing element of the one is in heat exchanging relation with the evaporative element of the other, whereby the volatilized refrigerant is condensed in the one system without the direct instrumentality of a compressor.

Referring in detail to the figure, the numeral 1 35 represents a stand pipe which as shown, extends through several stories of a building represented by the floor 2 and roof 3, and being directly connected to evaporating coils 4 located in several positions and on the several floors, said coils constituting the refrigerating elements of the 40 refrigerators 5. The upper end of the stand pipe

1, that is to say, the part which preferably extends above the roof, is connected to a tank 6 which as will presently be described, functions as a condenser. The stand pipe 1 as well as the evaporators 4 are maintained filled with liquefied refrigerant which normally stands at an intermediate level in the condenser tank 6. The stand pipe and the condenser tank are lagged with a layer 7 of insulation.

In performing their cooling function, the 10 evaporators 4 cause the liquefied refrigerant therein to boil, the vaporized refrigerant rising in bubbles through the column of liquid in the stand pipe 1 and through the body of liquid refrigerant in the tank 6 being condensed in said 15 tank. In order to determine a low boiling point for the refrigerant, it is preferred to maintain a vacuum in the atmosphere above the liquid column. This is accomplished by means of a fitting 20 8 adapted to be connected to a suitable vacuum pump, and a gage 9 is shown by means of which the degree of vacuum may be ascertained. The vacuum having once been produced, is perpetuated by sealing the fitting 8.

The stand pipe, evaporating coils and condenser tank form a closed hermetically sealed conduit for the refrigerant in which the refrigerant is always maintained below atmospheric pressure. In consequence the possibility of leakage is minimized since there is no internal pressure, and for the same reason, should through accident, a leak occur, the leakage will be into the system and not out of it, so that there will be no escape of the fumes into the atmosphere of 30 the building. The refrigerating system represented by the evaporators, stand pipe and condenser tank is characterized by the fact of the total absence of a compressor, adapting it ideally for apartment house service in view of the freedom of the system from the noise and vibration 35 incident to the use of a compressor.

The primary system thus far described, is interlinked with a secondary refrigeration system of any approved type and preferably located 40 on the roof, said system may comprise a compressor 10 and a motor 11 for running the same, a condenser 12, a reservoir 13 for the liquefied refrigerant, and an evaporating coil 14 to which the refrigerant is admitted through an expansion valve 15. The expansion valve is controlled 45 by a thermostat 16 located in the induction or low side of the compressor. The evaporating coil 14 is located in the condenser tank 6 and serves as the heat interchanging element for effecting 50 55

condensation of the refrigerant in the hermetic system.

The motor 11 is controlled by suitable means such as the sylphon actuated switch 17 operating 5 responsively to a thermostat 18 located in the condenser tank 6.

The location of the secondary refrigeration system on the roof places it entirely outside of the inhabited portion of the building and removes all objection to the use of the compressor 10 and to possible leakage of the gaseous refrigerant under the pressure which the compressor generates.

The operation of the interlinked or duplex refrigeration system is obvious. As the refrigerant boils in the several evaporators 4 and the height of the liquid column within the hermetic system diminishes, a point is reached where the thermostat 18 is warmed to the point where it 15 actuates the sylphonic switch 11 to start the motor 11 and put the secondary refrigeration system in operation. This cools and condenses the gaseous fraction of the refrigerant in the primary system restoring the column of liquefied 20 refrigerant to its normal height. When this has been accomplished the thermostat 18 has been cooled to the point where the sylphonic switch 25 operates to stop the motor 11 and the secondary refrigeration system becomes inactive.

In some climates the winter temperature on 30 the roof is sufficient to recondense the refrigerant without the assistance of the secondary refrigeration system. In such climates, it is preferred to provide an auxiliary air condenser 19 connected to the stand pipe 1 by means of a 35 conduit 20 and selectively automatically placed in communication with said conduit by means of a valve 21 controlled by a thermostat 22 responsive to atmospheric temperature. Normally, 40 that is to say, in the summer time, and whenever the air temperature is insufficient to produce the requisite condensation, the valve 21 is in closed position with respect to the air condenser so that the refrigerant in the primary 45 system is condensed in the tank 6 through the action of the secondary refrigeration system. When however, the air temperature sinks to a point at which it will promote condensation, the thermostat 22 opens the valve 21 to the air condenser and the condensation of the refrigerant 50 in the primary system is accomplished without the assistance of the secondary refrigeration system.

While I have in the above description disclosed 55 what I believe to be a preferred and practical embodiment of the invention, it is to be understood that the details of construction as shown are merely exemplary and intended to illustrate a broad principle, and that they are not to be construed as limiting the scope of the invention 60 as claimed.

What I claim is:

1. Refrigeration system comprising a primary 65 compressorless refrigeration system including a substantially vertical stand pipe and a plurality of evaporators connected into said stand pipe at different levels, a condenser tank with which the upper end of said stand pipe communicates, said stand pipe, evaporators and condenser tank forming an hermetic unit filled with liquid refrigerant up to an intermediate level in said tank, 70 and a secondary refrigeration system comprising an evaporator located in the condenser tank of said primary system and constituting the condensing element of said primary system, and

means responsive to temperature conditions in said primary system for periodically activating said secondary system.

2. Refrigeration system comprising a primary 5 compressorless refrigeration system including a substantially vertical stand pipe and a plurality of evaporators connected into said stand pipe at different levels, a condenser tank with which the upper end of said stand pipe communicates, said stand pipe, evaporators and condenser tank forming an hermetic unit filled with a liquid refrigerant up to an intermediate level in said tank, 10 and a secondary refrigerating system comprising an evaporator located in the condenser tank of said primary system and constituting the condensing 15 element of said primary system, and means responsive to said temperature conditions in said primary system for periodically activating said secondary system, said primary system with the exception of said condenser tank being adapted 20 to be housed within the habitable space of a building and said secondary system including the condenser tank of said primary system being adapted to be located outside of the habitable 25 space of said building.

3. Refrigeration system comprising a primary 30 compressorless refrigeration system including a substantially vertical stand pipe and a plurality of evaporators connected into said stand pipe at different levels, a condenser tank with which the upper end of said stand pipe communicates, said stand pipe, evaporators and condenser tank forming an hermetic unit filled with a liquid refrigerant up to an intermediate level in said tank, 35 and a secondary refrigerating system comprising an evaporator located in the condenser tank of said primary system and constituting the condensing element of said primary system, means responsive to said temperature conditions in said primary system for periodically activating said secondary system, an air condenser connected into 40 said stand pipe, and means responsive to atmospheric temperature changes for selectively shifting the communication of said stand pipe from said condenser tank to said air condenser, said primary system with the exception of said condenser tank being adapted to be enclosed within the habitable space of a building, said secondary system and said condenser tank and said air condenser being adapted to be located outside 45 of the habitable space of said building.

4. Refrigeration system comprising a primary 50 compressorless refrigeration system including a substantially vertical stand pipe and a plurality of evaporators connected into said stand pipe at different levels, a condenser tank with which the upper end of said stand pipe communicates, said stand pipe, evaporators and condenser tank forming an hermetic unit filled with a liquid refrigerant up to an intermediate level in said tank, 55 and the pressure in said primary system being less than atmospheric pressure, a secondary refrigerating system comprising an evaporator located in the condenser tank of said primary system and constituting the condensing element of said primary system, means responsive to said temperature conditions in said primary system for periodically activating said secondary system, an air condenser connected into said stand pipe, and means responsive to atmospheric temperature 60 changes for selectively shifting the communication of said stand pipe from said condenser tank to said air condenser, said primary system with the exception of said condenser tank being adapted to be enclosed within the habitable space of 65 said building.

a building, said secondary system and said condenser tank and said air condenser being adapted to be located outside of the habitable space of said building.

5 5. Refrigeration system comprising a primary compressorless refrigeration system, including a substantially vertical stand pipe and a plurality of evaporators connected into said stand pipe at different levels, a condenser tank with which 10 the upper end of said stand pipe communicates, said stand pipe, evaporators and condenser tank forming an hermetic unit filled with liquid refrigerant up to an intermediate level in said tank, and a second refrigeration system comprising an evaporator located in the condenser tank of said primary system and constituting the condensing element of said primary system, the pressure in the primary system being below atmospheric pressure.

20 6. Refrigeration system comprising a primary compressorless refrigeration system including a substantially vertical stand pipe and a plurality of evaporators connected into said stand pipe at different levels, a condenser tank with which 25 the upper end of said stand pipe communicates, said stand pipe, evaporators and condenser tank forming an hermetic unit filled with liquid refrigerant up to an intermediate level in said tank, and a second refrigeration system comprising 30 an evaporator located in the condenser tank

of said primary system and constituting the condensing element of said primary system.

7. Refrigeration system comprising a single stand pipe for refrigerant, evaporators at different levels connected to said stand pipe to receive liquid refrigerant therefrom and to discharge gaseous refrigerant thereinto, whereby the contents of said stand pipe constitutes an aerated column, the degree of aeration contributed by each super-located evaporator diminishing the weight of the head of said column on the sub-located evaporators.

5 8. Refrigeration system comprising a single stand pipe for refrigerant, evaporators at different levels, a single pipe connecting each evaporator to said stand pipe for receiving liquid refrigerant therefrom and discharging gaseous refrigerant thereinto, whereby the contents of said stand pipe constitute an aerated column, the degree of aeration contributed by each super-15 located evaporator diminishing the weight of the head of said column on the sub-located evaporators.

10 9. Refrigeration system as claimed in claim 7, including a condenser at the top of said stand pipe and a secondary refrigeration system having the evaporator thereof in heat exchanging relation to said condenser, the pressure in said stand pipe being maintained at less than atmospheric pressure.
